AIRFOIL

Edward F. Zaparka, Baltimore, Md., assignor to
 Zap Development Corporation, Baltimore, Md.,
 a corporation of Delaware

Application December 1, 1932, Serial No. 645,294
 Renewed December 9, 1936

30 Claims. (Cl. 244—42)

My invention relates to means for increasing the lift coefficient of airfoils and to means for effecting a lateral control of airplanes.

It is an object of my invention to make more positive and dependable the operation of mechanisms for increasing the lift coefficient of airfoils.

A further object of my invention is to make the lateral control of airplanes more definite in action and quicker in response to the pilot's actions.

A still further object of my invention is to accomplish the above objects with small weight, and with a mechanism having few parts which are easily repaired and replaced.

With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which, for the purpose of explanation, have been made the subject of illustration.

In the drawings:

Fig. 1 is a top plan view of an airplane equipped with my inventions, part of the wing and fuselage being broken away and positions of some of the parts being indicated by dotted lines.

Fig. 2 is a detailed sectional view taken on the line 2—2 of Fig. 1, looking in the direction of the arrows.

Fig. 3 is a detailed sectional view of the mechanism shown in Fig. 2 with the split flap mechanism in open position.

Fig. 4 is a detail view taken on the line 4—4 of Fig. 3, looking in the direction of the arrows.

Fig. 5 is a detail view of the flap mechanism, partly in section, showing a modification of the flap operating mechanism, the flaps being shown in open position.

Fig. 6 is a detail view taken along the line 6—6 of Fig. 5, looking in the direction of the arrows.

Fig. 7 is a sectional view taken on the line 7—7 of Fig. 1, looking in the direction of the arrows.

Fig. 8 is a sectional view similar to Fig. 7 of a modification in which the positioning of the upper flaps with respect to the airfoil is accomplished by cable control.

Fig. 9 is a top plan view of a modification of the flap operating mechanism, part of the wing structure being broken away.

Fig. 10 is a view taken along the line 10—10 of Fig. 9 looking in the direction of the arrows. 5

Fig. 11 is a detail view taken on line 11—11 of Fig. 9 looking in the direction of the arrows.

Referring to the drawings, I have shown in Figs. 1 to 4 inclusive and in Fig. 7 one form of my invention. Referring to Fig. 1 I have shown 10 an airplane comprising a fuselage 1, rear control surfaces comprising a rudder, a stabilizer and elevators which I have generally designated by the numeral 2, and a motor 3.

Looking down on top of the plane, as indicated 15 in Fig. 1, there is a left hand wing 4 and a right hand wing 5. There is indicated a pilot seat 6 in the fuselage. The pilot can control the opening of the split flaps by means of a handle 7 mounted on a sprocket, not shown, which drives 20 the sprocket chain 8, which in turn drives another sprocket wheel, not shown, mounted on a shaft 9.

Rotation of the shaft 9, as will be later described, controls the opening and closing of the split flap mechanism. In front of the pilot is 25 a control stick 11 which, upon movement to left or right, causes cable 12, which runs to the right-hand wing, to be wound or unwound on a drum 13. Likewise, there is a cable 14 which is wound or unwound on drum 13 by movement of the control stick 11. 30

The cable 14 controls the position of the flaps with respect to the airfoil on the left hand wing as the cable 12 controls the position of the flaps with respect to the airfoil on the right-hand wing. 35

The mechanism on the left-hand and right-hand wings is identical. The cables 12 and 14, in accordance with conventional design, pass over pulleys 15, then over other pulleys not shown, and then over pulleys 16. The cables are then extended to pass over pulleys 17, the cables returning and being joined together as indicated at 18. Upon movement of the control stick 11 the cables are made to move in each wing 4 and 5 in the same direction over the various pulley supports. 40 The cable 12 is pivotally attached to one end of a bell crank arm 19 of a bell crank lever which is pivoted at its middle point at 21. The bell crank lever has another arm 22 which is pivotally attached to a connecting rod 23 which is pivoted 45 at 24 to an operating arm or horn 25 attached to an upper flap 26 of the split flap construction.

Upon movement of the control stick 11 to either the left or right, because of the opposite pivoting of the bell crank levers, the upper flaps 55

26 on either wing are caused to move in opposite directions, thus setting the split flap construction at varying angles on the two wings upon movement of the control stick 11 from its perpendicular position, as shown in Fig. 1. If the control stick 11 is kept in a perpendicular position the relative positions of the split flap mechanisms with respect to the air foil are not changed and the setting of the flap construction on the right-hand wing 5 will be the same as on the left-hand wing 4. Where, however, it is desirable to effect lateral control, the movement of the control stick 11 will enable the pilot to cause the lift of one wing to be made relatively greater or less than that of the other wing.

It is to be noted that each operating arm or horn 25 is fixedly fastened to the top of the upper split flap member 26 which is provided with interior braces 27 which run between the nose 20 and the trailing edge of the upper flap. There is a bracing spar 28 at the front of the upper flap and a bracing spar 29 at the trailing edge. The upper flap has a support member 31 at its forward end which is hinged to support 32, carried 25 by the wing proper. The support 32 is mounted on and attached to a rear wing spar 33.

The wing is provided with bracing members 34 which pass from the rear wing spar 33 to a forward wing spar 35.

30 There is shown a lower flap member 36 which has a front bracing spar 37 and a rear bracing spar 38 and bracing members 39 between the spars. There is provided a link 41 which is pivoted at 42 to the upper spar at one end and has its lower end pivoted at 43 to an operating head 44. Also pivoted at 43 to the operating head 44 is another link 45 whose other end is pivoted at 46 to the bracing construction 39 of the lower flap member 36. The lower flap member has attached to its forward end a support member 47 which is pivoted on the support member 32 attached to the airfoil proper.

The support furnished through the support member 31 for the upper split flap member, and the support member 47 for the lower flap member being pivoted to the support 32 of the airfoil proper, permit the upper and lower flaps to be adjusted in unison with respect to the airfoil proper, and at the same time the relative position of the upper flap and the lower can be regulated as desired.

In Fig. 3 the lower flap is shown in open position with respect to the upper flap and in Fig. 2 the upper and lower flaps are shown in their closed position. By moving the operating rod 23 through the bell crank and cable connections previously described, both flaps can be moved.

The operating head 44 has screw threaded engagement with the screw threads 48 of an operating rod 49. The forward end of the operating rod 49 is universally connected at 51 to a drive shaft 52 which is journalled in the rear spar 33 of the wing. This universal connection is not described in detail as it is of the well known type. 65 The universal connection is located approximately in line with the hinging of the split flap construction to the wing section. In other words, a line drawn through the hinge points of the split flap construction with the airfoil proper will pass approximately through the center of this universal connection 51. This permits the universal connection to operate without catching or binding when the split flap construction is adjusted through the movement of the control stick 11. The drive shaft 52 which is journalled in the rear

spar 33 is provided with a frustoconical gear 53 which meshes with a frustoconical gear 54 carried by the shaft 9.

Upon rotation of the shaft 9 through operation of the handle 7 from the pilot seat, the similar conical gears 54, which engage similar gears 53 fitted at various stations on the wing section, cause rotation of the drive shafts 52, and through the universal connections 51 the operating rods 49 are rotated to move the operating heads 44 to cause the links 41 and 45 to open or close the split flaps, as is clearly apparent from Figs. 2 and 3.

Referring to Fig. 7 it will be seen that the bell crank levers are pivoted on brackets 55 which are attached to the front wing spars 35. This permits the bell crank levers to pivot in a plane approximately parallel to a plane passing through the wing chords, and the construction is of sufficient rigidity to insure easy and positive reciprocation of the connecting rods 23.

In operation let us assume that the control stick 11 is in the position shown in Fig. 1, in which case by manipulation of the handle 7 the lower split flap members 36 can be caused to assume a position such as shown in Fig. 7 or Fig. 3. This increases the lift and the drag on the wing section and the lift coefficient for both airfoils is increased. To effect lateral control the control stick 11 may be moved from its position shown in Fig. 1 either to the left or right, in which case the split flap construction on one wing will be raised or lowered with respect to that of the other wing.

Let us assume that the control stick 11 is moved to a position to cause the split flap construction on the right wing to be raised. This will tend to decrease the lift coefficient for that wing at the same time the corresponding flap construction on the left-hand wing has been lowered, which will increase the lift coefficient for that wing and thus effect a rolling moment. Yawing moments are also produced by the drag of the flaps, which has an effect on the maneuverability of the ship.

Referring to Fig. 5, I have shown a modification in which the operating rod 49 has its end remote from the universal connection 51 journalled in a bearing block 56 which is attached to the bracing member 27 of the upper split flap member 26. The operating head 57 is provided with stub shafts 58 to which are pivoted two links 59, the links being held in position on the stub shafts 58 by washers 61 and pins 62 which pass through the stub shafts 58. The operating head 57 is provided with grooves 63 which fit over slide members 64 formed on the bracing members 27 of the upper split flap member 26. The other end of links 59 are pivoted at their ends 65 to a shaft 66 which passes through the bracing construction 39 of the lower split flap member 36. This construction is provided with washers 67 and pins 68 to hold the links 59 in operative position.

In the construction shown in Figs. 5 and 6, upon rotation of the operating rod 49 the operating head 57 is caused to slide along its support 65 and the links 59 open and close the split flap members.

In Fig. 8 I have shown the upper flap member 26 provided with an operating arm or horn 71 mounted on the underside of the upper flap member and below the operating arm or horn 25. The operating arm 71 is attached in some suitable manner to the front bracing or spar member 28 of the upper split wing flap member. Attached to the extremities of the operating arms

or horns 25 and 71 are cables 72 and 73, respectively, which pass through apertures into the interior of the wing proper and around pulleys 74 and 75, respectively, which are attached to the front wing spar 35. One of the cables 72 for each wing passes over the drum 13 and the other cable is attached to a similar cable for the corresponding wing. This cable construction permits the pilot, upon movement of the control stick 11, to change the position of the split flap member with respect to the airfoil proper, as is accomplished in the construction previously described and employing a stiff connecting rod 23 instead of cables.

15 Referring to Fig. 9, I have shown a form of construction in which the operating links, adapted to move the lower flap with respect to the upper flap to open and close the split flap construction, are mounted to pivot on axes which 20 are substantially parallel to the longitudinal axis of the fuselage; in other words, at substantially right angle to the axes at pivoting of the links heretofore described. Here the upper flap 26 is controlled as shown in the form of invention 25 illustrated in Figs. 1, 2, 3, 4, 5, and 7. The mechanism, however, for opening and closing the flaps with respect to each other is, as above indicated, different.

Shaft 9, which is caused to rotate through 30 chain and sprocket connections by movement of the handle 7 of the pilot, carries a bevel gear 76 which engages the bevel gear 77 rotating drive shaft 78, thus causing the universal connection 79 to rotate to cause rotation of a shaft 81 which 35 is supported at 82 on the bracing construction of the upper flap member. The shaft 81 carries a bevel gear 83 which meshes with a bevel gear 84 carried by an operating shaft 85 which is suitably journaled, as indicated at stations 86, on 40 the bracing members of the upper split flap member 26.

The rod 85 is adapted to be rotated and has, at 45 suitable stations thereon, screw threaded sections 87 which engage with interior screw threads on operating heads 88. The operating heads 88 have pivotally mounted thereon links 89 whose lower ends are pivoted at 91 to blocks 92 which are attached by stub shafts 93 to supports 94, suitably mounted on and attached to the lower 50 split flap member 36.

Upon rotation of shaft 9, through the bevel gears 76 and 77 and bevel gears 83 and 84, shaft 85 is caused to rotate, which moves operating heads 88, and through links 89 the lower flap is caused to move with respect to the upper flap to 55 open or close the split flap construction.

While I have shown and described the preferred embodiment of my invention, I wish it to be understood that I do not confine myself to the 60 precise details of construction herein set forth, by way of illustration, as it is apparent that many changes and variations may be made therein, by those skilled in the art, without departing from the spirit of the invention, or exceeding the scope 65 of the appended claims.

I claim:

1. A device of the character described comprising an airfoil, split flap members hingedly attached to said airfoil and both movable with 70 respect thereto, link members without the air-stream over the flap surfaces carried by the flap members for opening and closing the flaps, and operating means for the links universally connected at the point of hinged attachment.

2. A device of the character described compris-

ing an airfoil, split flap members, both movable with respect to the airfoil and hinged thereto, a rotatable operating rod, a universal connection for the rod at the hinge point, mechanism operated by said rod for opening and closing the flaps, said mechanism being without the air-stream over the flap surfaces and means to rotate the operating rod.

3. A device of the character described comprising an airfoil, split flap members pivotally supported for motion at the rear of the airfoil and hinged thereto, a rotatable drive shaft, a universal flexible connection operated by the drive shaft having universal movement through the hinge point, and means on the flap members with- 10 out the air stream over the flap surfaces operated through the rotation of the flexible connection to move the flap members relative to each other.

4. A device of the character described comprising an airfoil, split flap members, both movable with respect to the airfoil and hinged thereto, a rotatable operating rod, a universal connection for rotating the operating rod located at the hinge point, members without the airstream over the flap surfaces operating through said rotation 25 thereof to open and close the flap members, and a drive shaft connected to the universal connection.

5. A device of the character described comprising an airfoil, split flap members hingedly attached to said airfoil, both movable with respect thereto, a stiff connection rod operatively connected to one flap, means to reciprocate the rod, and link members carried by the flap members for opening and closing the flaps, said link members being without the airstream over the flap 35 surfaces.

6. A device of the character described comprising an airfoil, split flap members, both movable with respect to the airfoil, a stiff connection 40 rod operatively connected to one flap, means to reciprocate the rod, a rotatable operating rod, mechanism without the airstream over the flap surfaces operated by said rod for opening and closing the flap, and means to rotate the op- 45 erating rod.

7. A device of the character described comprising an airfoil, hinged split flap members pivotally supported for motion at the rear of the airfoil, a stiff connection rod operatively connected to one flap, means to reciprocate the rod, a rotatable drive shaft, a universal flexible connection operated by the drive shaft, and means on the flap members operated through the rotation of the flexible connection to move the flap members relative to each other, said means being without the airstream over the flap surfaces.

8. A device of the character described comprising an airfoil, split flap members, both movable with respect to the airfoil, a stiff connection 60 rod operatively connected to one flap, means to reciprocate the rod, a rotatable operating rod, a universal connection for rotating the operating rod, an operating head engaging screw-threads on said operating rod and movable by rotation 65 thereof, links without the airstream over the flap surfaces hinged at one end to the upper and lower split flap members and at their other end to the operating head to open and close the flaps, and a drive shaft connected to the universal connec- 70 tion.

9. A device of the character described comprising an airfoil, split flap members, both movable with respect to the airfoil and hinged thereto, a rotatable operating rod, a universal connection 75

for rotating the operating rod located at the hinge point, an operating head engaging screw-threads on said operating rod and movable by rotation thereof, means without the airstream over the flap surfaces engaging said head to open and close the flaps, and a drive shaft connected to the universal connection.

10. A device of the character described comprising an airfoil, split flap members, both movable with respect to the airfoil and hinged thereto, a rotatable operating rod, a universal connection for rotating the operating rod located at the hinge point, an operating head engaging screw threads on said operating rod and movable by rotation thereof, links without the airstream over the flap surfaces hinged at one end to the upper and lower split flap members and at their other ends to the operating head to open and close the flaps, and a drive shaft connected to the universal connection.

11. A device of the character described comprising an airfoil, split flap members, both movable with respect to the airfoil, a stiff connection rod operatively connected to one flap, means to reciprocate the rod, a rotatable operating rod, a universal connection for rotating the operating rod, an operating head engaging screw threads on said operating rod and movable by rotation thereof, links without the airstream over the flap surfaces hinged at one end to the upper and lower split flap members and at their other end to the operating head to open and close the flaps, and a drive shaft connected to the universal connection.

12. A device of the character described comprising an airfoil, split flap members, both movable with respect to the airfoil, a rotatable operating rod supported by and movable with the upper flap only, a universal connection for operating the rotating rod, members operating through said rotation thereof to open and close the flap members, and a drive shaft connected to the universal connection.

13. A device of the character described comprising an airfoil, split flap members, both movable with respect to the airfoil, a rotatable operating rod supported by and movable with the upper flap only, a universal connection for rotation of the operating rod, an operating head engaging screw threads on said operating rod and movable by rotation thereof, means engaging said head to open and close the flaps, and a drive shaft connected to the universal connection.

14. A device of the character described comprising an airfoil, split flap members, both movable with respect to the airfoil, a rotatable operating rod supported by and movable with the upper flap only, a universal connection for rotation of the operating rod, an operating head engaging screw threads on said operating rod and movable by rotation thereof, a link pivoted to the lower flap at one end and to the operating head at the other to open and close the flap on rotation of the operating rod, and a drive shaft connected to the universal connection to rotate the operating rod.

15. A device of the character described comprising an airfoil, split flap members, both movable with respect to the airfoil and having hinged connection therewith, means to move both flap members with respect to the airfoil, a link fixed to a fixed pivot on one flap, a movable pivot for the other end of the link on the other flap, said movable pivot being capable of movement in a direction substantially perpendicular to the axis

of rotation of said hinged connections, and means to move the movable pivot to open and close the flaps.

16. A device of the character described comprising an airfoil, split flap members, both movable with respect to the airfoil and having a hinged connection therewith, a rotatable operating rod, a universal connection for rotation of the operating rod, a link fixed to a fixed pivot on one flap, a movable pivot for the other end of the link adapted to move on rotation of the operating rod in a direction substantially perpendicular to the axis of rotation of said hinged connections to open and close the flaps.

17. A device of the character described comprising an airfoil, split flap members hingedly attached to said airfoil and both movable with respect thereto, a stiff connection rod operatively connected to one flap, a bell crank lever having one of its ends connected to one end of the connection rod, means to rotate the bell crank lever to reciprocate the connection rod, and link members carried by the flap members without the airstream over the flap surfaces for opening and closing the flaps.

18. A device of the character described comprising an airfoil, split flap members hingedly attached to said airfoil, both movable with respect thereto, a stiff connection rod operatively connected to one flap, a bell crank lever having one of its ends connected to one end of the connection rod, means to rotate the bell crank lever to reciprocate the connection rod, a rotatable operating rod, a universal connection for rotating the operating rod, members without the airstream over the flap surfaces operating through said rotation thereof to open and close the flap members, and a drive shaft connected to the universal connection.

19. A device of the character described comprising an airfoil, split flap members pivotally connected to and movable with respect to the airfoil, upper and lower operating arms attached to one of the flap members, cables attached to the arms to operate said flap member, a rotatable operating rod, a universal connection for rotation of the operating rod, means without the airstream over the flap surfaces operating through said rotation thereof to open and close the flap members, and a drive shaft connected to the universal connection.

20. A device of the character described comprising an airfoil, split flap members hingedly attached to said airfoil, both movable with respect thereto, a stiff connection rod operatively connected to one flap, a bell crank lever having one of its ends connected to one end of the connection rod, means to rotate the bell crank lever to reciprocate the connection rod, a rotatable operating rod, a universal connection for rotation of the operating rod, an operating head engaging screw threads on said operating rod and movable by rotation thereof, means without the airstream over the flap surfaces engaging said operating head to open and close the flaps, and a drive shaft connected to the universal connection.

21. A device of the character described comprising an airfoil, split flap members pivotally connected to and movable with respect to the airfoil, upper and lower operating arms attached to one of the flap members, cables attached to the arms to operate said flap member, a rotatable operating rod, a universal connection for operation of the operating rod, an operating head engaging the screw threads on said operating rod,

- and movable by rotation thereof, means without the airstream over the flap surfaces engaging said operating head to open and close the flaps, and a drive shaft connected to the universal connection. 5
22. A device of the character described comprising an airfoil, split flap members, both movable with respect to the airfoil and having hinged connection therewith, means to move both flap members with respect to the airfoil, a link fixed to a fixed pivot on one flap, a movable pivot for the other end of the flap carried by the other flap, a rotating operating rod, a universal connection for rotation of the operating rod, means operating through said rotation thereof to move the movable pivot in a direction substantially parallel to the axis of rotation of said hinged connection to open and close the flaps, and a drive shaft connected to the universal connection. 10
23. A device of the character described comprising an airfoil, split flap members, both movable with respect to the airfoil and having a hinged connection therewith, means to move both flap members with respect to the airfoil, a link fixed to a fixed pivot on one flap, an operating head to which the other end of the link is pivoted, an operating rod carried by the upper flap having screw threaded engagement with said operating head, and a drive shaft connected to the universal connection for rotating the operating rod to move the operating head and open and close the flaps. 15
24. A device of the character described, comprising an airfoil and flap adapted to be moved below the airfoil and hinged thereto, a rotatable operating rod, a universal connection for the rod at the hinge point, mechanism without the airstream over the flap surfaces operated by said rod for moving the flap on its hinge point, and means to rotate the operating rod. 20
25. A device of the character described, comprising an airfoil, a flap supported for movement below the airfoil and hinged thereto, a rotatable drive shaft, a flexible connection operated by the drive shaft, having universal movement through the hinge point, and means without the airstream over the flap surfaces on the flap member operated through the rotation of the flexible connection to move the flap up and down. 25
26. A device of the character described, comprising an airfoil, a flap located near the rear of the airfoil for movement below the airfoil, a rotatable operating rod which may be held fixed with respect to the flap, an operating head for movement on the rod, a link without the airstream over the flap surfaces joining the operating head and the flap whereby the flap may be moved upwardly and downwardly. 30
27. A device of the character described, comprising an airfoil, a flap adapted to be moved below the airfoil and hinged thereto, a rotatable operating rod, a universal connection for the rod at the hinge point, a fixed pivot on the flap, a link substantially without the airstream over the flap surfaces pivoted on said fixed pivot, means moved by the operating rod to cause the link to raise and lower the flap, and means to rotate the operating rod. 35
28. A device of the character described, comprising an airfoil, a flap supported for movement below the airfoil and hinged thereto, a rotatable drive shaft, a flexible connection operated by the drive shaft having universal movement through the hinge point, an operating rod driven through said flexible connection, an operating head on the rod, toggle links substantially without the airstream over the flap surfaces pivoted on the operating head, at least one of which is pivoted to the flap to move the flap into raised and lowered positions. 40
29. A device of the character described comprising an airfoil, a flap located near the rear of the airfoil for movement below the airfoil, a rotatable operating rod which may be held fixed with respect to the flap, a hinged connection for the flap near its front edge, an operating head for movement on the operating rod, a link for movement on the operating rod toward and from the hinged connection for the flap, and a link without the airstream over the flap surface joining the operating head and the flap whereby the flap may be moved upwardly and downwardly. 45
30. A device of the character described comprising an airfoil, a flap located near the rear of the airfoil for movement below the airfoil, a hinged connection for the flap upon which it pivots, a rotatable operating rod which may be held fixed with respect to the flap, an operating head for movement on the rod in a direction substantially parallel to the axis of rotation of the flap about its hinged connection, and a link without the airstream over the flap surface joining the operating head and the flap whereby the flap may be moved upwardly and downwardly. 50

EDWARD F. ZAPARKA.
